UNITED STATES PATENT OFFICE.

MILTON E. WINANS, OF LONG ISLAND CITY, NEW YORK.

CURRENT-MOTOR.

1,204,629.

Specification of Letters Patent.

Patented Nov. 14, 1916.

Application filed March 15, 1916. Serial No. 84,331.

To all whom it may concern:

Be it known that I, MILTON E. WINANS, a citizen of the United States, residing at Long Island City, in the county of Queens and State of New York, have invented new and useful Improvements in Current-Motors, of which the following is a specification.

This invention relates to improvements in devices for transforming the force of a flowing stream into useful energy, so that the power derived from the current may be applied to any purpose for which motors are used.

The principal object is to provide a motor applicable to any stream or river, irrespective of the rapidity of its current, and of any desired capacity compatible with the size of the stream, so that the whole or a part of the entire current may act upon it.

Another object is to provide a motor of relatively cheap construction, which requires no special care or supervision after its installation, and in which the full force of the current is utilized.

These and other objects are attained by the novel construction and combination of parts hereinafter described and shown in the accompanying drawing, forming a material part of this disclosure, and in which—

Figure 1 is a general plan view showing an embodiment of the invention, the cover being partially removed, and Fig. 2 is a sectional view taken substantially on lines 2—2 of Fig. 1.

In the installation of the device it is usually necessary to divert the stream temporarily or to erect a coffer-dam so that the location for the foundation of the superstructure may be clearly determined, and suitable excavation made for receiving the same. This excavation need not extend far below the bed of the stream, only sufficient to obtain a firm and secure foundation being necessary. This will be clearly evident upon examination of the drawing, particularly Fig. 2, in which the foundation 10 is shown to extend slightly below the stream bed 11, the foundation being made of hydraulic cement or the like, which, when set is

unaffected by the movement of the stream.

One part of the foundation is extended vertically upward, forming an abutment 15, the same having an exterior semi-circular profile 16 and a hub portion 17, the latter being concentric with the outer portion, and

of considerable smaller radius. Extending between these portions, and joined at their outer ends by curves 18 and 19, are straight surfaces 20 and 21, the same being tangential to a line drawn between the center of the abutment and the hub 17. Inserted in the center of the hub 17, is a bushing 23 having a flange 24, the bushing being bored to receive the lower end and form a foot bearing for a vertical shaft 25 having a flange 26 to which is rigidly secured a circular plate 27, the radius of which is slightly greater than that of the semi-circular wall 16, so as to extend beyond it. Secured to the periphery of the plate 27 and equally spaced around it are a plurality of bars 30 extending downwardly nearly or quite to the upper surface of the foundation 10 and having pivotally mounted on them rectangular plates or vanes 32 adapted to swing freely thereon. Also attached to the lower side of the plate 27 are bracket elements 33, having a portion 34, placed on the plate, in such position that when the vanes 32 contact with them that the vanes will also be radial with respect to the device, the brackets passing through a curved recess 22 formed in the top of the abutment 15. In Fig. 1 other raised blocks 35 are shown, the same indicating the foundation for such building or superstructure which may be desired to erect with relation to the motor in the stream, and which are used to control the guides or mountings for the vertical shaft 25.

In operation, the stream running in the direction indicated by the arrows, will impinge upon the blades 32 directly that their extreme inner ends pass the curved point 19, swinging clear of the straight portion 21 of the abutment, and assume a position as indicated by the drawing, that is make contact with the uprights 34, so that the pressure of water causes the plate 27 to rotate, through its connections, carrying with it the shaft. When, however, the inner ends of the vanes make contact with the wall 20 of the abutment, they are caused to move outwardly, swinging freely upon the pivots 30 so as to be inoperative by the current and are brought consecutively around the curved surface of the abutment until they pass the curve 19.

While I have thus far described an embodiment of the invention, modifications may be made without departing from the

general scope of the claims hereto appended, and I therefore do not desire to be held strictly to the construction shown.

Having thus described my invention, what I claim as new and desire to secure by Letters Patent, is:—

1. In a current motor, the combination with a foundation fixed in the bed of a stream, of a submerged, rigid abutment formed with said foundation, said abutment having a cam profile, a shaft mounted concentric to the curved portions of said abutment, a plate carried by said shaft adapted to rotate thereover, a plurality of vanes pivoted pendant to said plate, and means combined with said plate whereby said vanes are held radial when opposed to the flow of the current, whereby said plate and shaft are caused to rotate.
2. In a current motor, the combination with a foundation fixed in the bed of a stream, of an abutment formed with said foundation, said abutment extending vertically above the foundation and having an arcuate profile joined by straight lateral surfaces to an arcuate hub portion of lesser radius than its main portion, a shaft mounted central of the hub, a circular plate attached to said shaft, said plate extending beyond the confines of said abutment, a

plurality of pendant vanes hingedly engaged at the periphery of said plate, means on said plate adapted to engage with said vanes whereby they are held radial during a portion of their movement and means formed with said abutment whereby said vanes are caused to move tangentially during the remainder of their movement.

3. In a current motor, a circular plate mounted to rotate on a vertical axis, a plurality of rectangular vanes pivoted vertically at one of their shorter edges at uniform intervals near the periphery of said plate, a level horizontal surface over which said vanes operate, a fixed abutment having oppositely disposed arcuate lateral surfaces extending upward to a height equivalent to the width of said vanes, one of the arcuate surfaces having a radius complementary to the length of said vanes between the axis of the plate and vanes respectively, the other arcuate surface having a radius slightly within the pivotal point of said vanes, means on said plate adapted to maintain said vanes radial when opposed to the current, and means for utilizing the rotary motion imparted to said plate by said vanes.

In testimony whereof I have signed my name to this specification.

MILTON E. WINANS.
